The ornamental design for a work vehicle boom, as shown and described.

DESCRIPTION

FIG. 1 is a top, rear, left perspective view of a work vehicle boom embodying our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a top, rear, right perspective view of a work vehicle boom according to another embodiment of our new design, the various views thereof being mirror images of the views shown in FIGS. 2-7.

The broken line representations in the figures show unclaimed environment or boundaries, and thus form no part of the claimed design.

The nature of this product is a boom arm for a work vehicle, such as a skid steer loader.
